UNITED STATES PATENT OFFICE.

DAVID BOURQUE, OF AMESBURY, MASSACHUSETTS, ASSIGNOR TO G. W. J. MURPHY CO.,
OF MERRIMAC, MASSACHUSETTS, A CORPORATION OF MASSACHUSETTS.

FOUNDING-PATTERN.

1,287,625.

Specification of Letters Patent. Patented Dec. 17, 1918.

Application filed July 11, 1916. Serial No. 108,696.

To all whom it may concern:

Be it known that I, DAVID BOURQUE, a subject of the King of Great Britain, and a resident of Rocky Hill, Amesbury, in the county 5 of Essex and Commonwealth of Massachusetts, have invented an Improvement in Founding-Patterns, of which the following description, in connection with the accompanying drawings, is a specification, like 10 characters on the drawings representing like parts.

This invention relates to foundry patterns for making molds for castings. One aim of the invention is to provide a pattern by the 15 use of which a mold can be easily and quickly made from which castings can be produced with the parts thereof that formed respectively in the cope and the drag in perfect 20 relative position. My invention is particularly applicable to the production of small castings such as the heads or buttons of certain fasteners of the kind shown in the patent to Murphy, No. 853,206. To illustrate 25 my invention I have herein shown an embodiment thereof adapted to be used in making such buttons or heads.

My invention will be best understood by reference to the following description, taken in connection with the accompanying drawings, wherein:

Figure 1 is a top plan view of a portion of one form of pattern constructed in accordance with my invention;

Fig. 2 is a bottom plan thereof;

35 Fig. 3 is a section on line 3—3 of Fig. 2, on a larger scale;

Fig. 4 is a section showing how the mold is formed; the longer dimension of the plate 3 in this figure is on a vertical line as regards Figs. 1 and 2, but the scale is larger than in those two figures;

Fig. 5 is a plan view of the casting as taken from the mold;

Fig. 6 is a section on line 6—6 of Fig. 5; 45 and

Fig. 7 is a view of one of the buttons as cut from the casting.

First describing the pattern in a general way and referring particularly to Figs. 1, 50 2 and 4, I have shown a pattern comprising a body plate 3 of a size substantially that of the cope 5 and drag 7 of the flask, as shown in Fig. 4. One side of this plate may be provided with a projecting ingate- 55 forming portion 9 and with projections 11

to form the main runners, from which branch the subsidiary runner or spray-forming portions 13. In Figs. 5 and 6, which show the casting, the parts produced in the portions of the mold formed by these projections are marked with the same numerals modified by the letter *a*. At suitable points along the runners 13 mating projections 15 and 17 extend on opposite sides of the plate, and these projections are complementary and 60 conjointly have the form of the desired casting. Referring to Fig. 7, it will be observed that one part 15^a at one side of line *a*—*a* of the casting corresponds in shape and size to the projection 15, and the remaining portion 70 17^a on the other side of the line corresponds to the projection 17.

To form a mold the body plate 3 is assembled with the cope 5 and drag 7, as shown in Fig. 4, sand 19 is supplied and suitably 75 pressed in place. It will be apparent that when the parts of the flask are reassembled without the plate a mold will be formed having recesses corresponding to the various projections from the plate and that the 80 thickness of the plate itself will not affect its form, the surfaces of the sand 19 which come in contact with the opposite faces of the plate in Fig. 4 coming together at the “parting” of the mold. That is, the form of 85 the casting taken from the mold is the same as that of the pattern with the plate 3 reduced in thickness to the vanishing point, and, of course, with an ordinary sink-head on the part 9^a. 90

By reference to Fig. 3 it will be seen that I prefer to make one of the complementary projections that go up to make the finished casting (shown in Fig. 6), such as the part 15, of considerably greater depth than the 95 other part 17. Preferably also I arrange the projections of alternate sprays 13 along the runners 11 oppositely so that, longitudinally of the runner a deep major part 15 succeeds a shallow minor part 17, and so on. 100 By this arrangement deep matrices closely adjacent each other, and separated by thin walls of sand, are avoided and the matrices can be placed much more closely together in the mold, and the output of completed castings considerably increased. The arrangement is shown necessarily exaggerated in proportion, in Fig. 4. 105

It will be apparent that if perfect castings are to be produced, it is important that the 110

complementary projections be exactly alined and this is particularly important if the parts themselves have a characteristic shape. For example, in the case of the button such as is shown in Fig. 7, the rear part 17^a is curved transversely on the arc of a circle and depressed centrally as at 21^a to permit a hole to be easily drilled therein. It is important that the flattened portion be centered and that the curved back be symmetrical as regards the body of the button. To insure the proper positioning of the projections 15 and 17 and also to simplify the construction of the pattern, I utilize as a guide holes 27 extending through the plate 3 which may readily be cut perpendicularly to the surface thereof. Preferably, I form the projections as the end portions of separate members 23 (see Fig. 3) having an intermediate portion 25 of a length equal to the thickness of the plate 3. The member 23 may be inserted in an aperture 27 formed in plate 3 which is shaped to receive snugly the intermediate portion 25. It is obvious that the end portions 15 and 17 projecting from the faces of the plate will be in perfect alinement and as the members 23 can be easily constructed with accuracy the completed casting will have the proper contour. In fact, the entire process of constructing the pattern is simplified and cheapened.

The parts 9, 11 and 13 which form respectively the ingate or basin, the main runner and the sprays, may, if desired, be constructed as shown of suitably formed pieces secured in any suitable manner to the plate 3.

I have herein described the particular form of pattern illustrated in the drawing in detail, and have used specific words in referring to the various parts thereof, but it will be understood that my purpose in so doing was to make possible a more ready un-

derstanding of the illustrative embodiment of my invention herein disclosed and not because the details of construction and application are essential. 45

What I do claim and desire to secure by Letters Patent is:

1. A pattern for forming molds for casting articles comprising a plate substantially of the size of the flask having a plurality of apertures therethrough, members secured in said apertures each having a major end portion projecting from one side of the plate in form like a major part of the desired casting and a minor end portion projecting from the other side of the plate in form like the complementary part of the casting, said major portions being distributed substantially in alternation on opposite sides of the plate whereby the matrices may be nearer together in the mold. 50 55

2. A pattern for forming molds for casting articles comprising a plate having pairs of opposed projections on the sides thereof, the elements of each pair being directly opposite each other and on oposite sides of the plate, one element being in form like a major part of the desired casting and the other like the complementary minor part, said major portions being distributed substantially in alternation on opposite sides of the plate whereby the matrices may be nearer together in the mold. 60 65 70

3. A pattern for forming molds for casting articles having projections from a face thereof, certain of said projections being in form like a major portion of the desired casting and others like the complementary minor portion, projections of different character being disposed in alternation. 75 80

In testimony whereof, I have signed my name to this specification.

DAVID BOURQUE.
